UNITED STATES PATENT OFFICE.

JAMES E. ALLISON, OF ST. LOUIS, MISSOURI, ASSIGNOR TO GEORGE M. SEELEY, OF NEW YORK, N. Y.

SIGNALING SYSTEM.

No. 804,820.

Specification of Letters Patent.

Patented Nov. 21, 1905.

Application filed May 4, 1904. Serial No. 206,366.

To all whom it may concern:

Be it known that I, JAMES E. ALLISON, a citizen of the United States, residing at St. Louis, Missouri, have invented a certain new and useful Improvement in Signaling Systems, of which the following is a full, clear, and exact description, such as will enable others skilled in the art to which it appertains to make and use the same, reference being had to the accompanying drawings, forming part of this specification, in which—

Figure 1 is a diagrammatic view illustrating the system, only one signaling-station being indicated. Fig. 2 is a side elevation of the switch. Fig. 3 is a top plan view of the same. Fig. 4 is a transverse sectional view through the contact-disk, ratchet, and pawl of said switch. Fig. 5 is a side elevation of the contact-carrying disk of said switch, and Figs. 6 and 7 are detail views illustrating the switch-actuating mechanism, and Fig. 8 is a detail view illustrating the mechanism for sending the "answering-back" signals.

This invention relates to improvements in signaling systems, being more particularly an improvement upon the system forming the subject-matter of my application for patent, filed August 14, 1902, Serial No. 119,639.

Generally speaking, the system includes a home or central station and a plurality of signal or distant stations. Each signal-station is provided with a signal which is under the control of a switch, there being one switch for each signal. At the home station is a sending instrument which controls the various before-mentioned switches. The switches are given step-by-step movement through the instrumentality of said sending mechanisms and are so set that each switch is brought into operative position at a time different from that at which any other of said switches is brought into operative position.

One object of the present invention is to provide means whereby the various before-mentioned switches can be readily corrected or properly set with relation to each other.

A further object is to provide means whereby the signals at the various distant stations can be both thrown and reset from the home station.

A further object is to provide means whereby the circuit which controls the magnet for operating each before-mentioned switch is positively made and broken for each step of

such switch, and a further object is to provide an improved construction of switch for use in systems of the character of the present.

To these ends and also to improve generally upon systems of the character indicated and upon the apparatus employed in such systems the invention consists in the various matters hereinafter described and claimed.

Referring now more particularly to the drawings, A represents the home station, and B indicates one of the signal or distant stations. Each signal-station is provided with a suitable signal, such as the paddle C, the paddle being here shown as fixed to the rotatable shaft 1, and this shaft being connected to a shaft 2 by means of a sprocket-chain 3, which runs over sprocket-wheels 4 and 5 upon the respective said shafts. Upon the shaft 2 is a catch 6, adapted to be engaged by a movable latch or hook 7, which is formed upon one end of a pivoted armature. When the said latch engages the said catch, as shown by full lines in Fig. 1, the signal-paddle C is held in elevated or safety position, and when the said latch is thrown out of engaging position the weight of said signal-paddle causes the same to fall into operative or danger position, as shown by dotted lines in said figure.

At each signal-station is a solenoid D, whose helix 8 is in the line-circuit 9, this line-circuit being conveniently the trolley-circuit for operating the cars upon the road, so that the solenoid is subjected to the influence of the heavy circuit from the dynamo, such circuit usually carrying about five hundred volts. The core 10 of said solenoid is connected to the said shaft 2, as by means of a chain 11, connected to a drum 12 upon said shaft. Normally the solenoid D is deenergized, and when the signal-paddle C falls the core 10 is partly withdrawn from the helix. When, however, the said solenoid is energized, the core 10 is drawn into the helix, and the shaft 2 is rocked to elevate the signal and cause the same to be locked in elevated position, all as will be readily apparent.

The latch-armature 7 is controlled by a magnet 13, which is in a circuit including a local battery 14, said circuit also including a relatively fixed terminal 15 and a movable terminal 16, the latter being conveniently a pivoted armature. The said circuit also includes a second relatively fixed terminal 17 and a second movable terminal 18, with which said terminal

17 coöperates. As here shown, the terminal 18 is a conducting-strip in a rotatable disk 19, which is mounted upon a rotatable shaft 20, said shaft being included in the said circuit and having mounted thereon a ratchet-disk 21, with which a pawl 22 coöperates. It will now be apparent that if the disk 19 be moved to bring the terminal 18 into contact with the terminal 17 (the latter being a brush resting upon the periphery of said disk 19) and if the terminal 16 be brought into contact with the terminal 15 the circuit including the local battery 14 will be closed, whereupon the magnet 13 will be energized, the latch-armature 17 will be thrown from detaining position, and the signal-paddle C will be permitted to fall. The circuit 9 for controlling the solenoid D has separated terminals 23, with which a movable connector or bridge-piece 24 is adapted to contact, said bridge-piece being carried upon the core 25 of a solenoid E, whose helix is marked 26. This helix is in the circuit which includes said local battery 14, said terminals 15 and 16, and said terminal 18, said last-mentioned circuit also including a brush 27, which rests upon the periphery of said before-mentioned disk 19. The brush 27 is set one step behind the before-mentioned brush 17. In its rotation the said disk 19 first brings the terminal 18 into contact with the terminal 17, whereupon the magnet 13 is energized and the signal-paddle falls, as heretofore explained. At its next step the said disk 19 carries the terminal 18 out of contact with the terminal 17 and brings said terminal 18 into contact with the terminal 27, thus deënergizing the magnet 13 and energizing the helix 26, whereupon the bridge conductor 24 completes the circuit 9, which controls the solenoid D, and the signal-paddle is thus thrown into its normal safety position. A second local battery 28 is included in a circuit which includes a magnet 29, upon whose armature 30 is pivotally mounted the before-mentioned pawl 22, and the said last-mentioned circuit also includes a fixed terminal 31 and a movable terminal 32, the latter being in the present instance the armature of a polarized magnet F, one of the poles of said magnet being marked 33 and the other 34. Manifoldly, when a current of one polarity is sent through said magnet F the pole 34 is energized and the armature-terminal 32 is thrown into contact with the terminal 31, whereupon the circuit including the magnet 29 is completed and the pawl 22 is actuated to move the disk 19 through one step. When a current of opposite polarity is sent through the magnet F, the pole 33 is energized and the armature 32 is moved to positively break said circuit which includes said magnet 29. The magnet F being energized the proper number of times, any desired disk 19 can be brought into circuit-forming position. A magnet 34^a is adapted when energized to attract the armature-terminal 16 and is included in a circuit

with the battery 35 at the home station. As the circuit which includes the magnet 13 also includes the terminals 15 and 16 and the terminals 17 and 18 and as the circuit which includes the solenoid E also includes the terminals 15 and 16 and the terminals 18 and 27, neither the magnet 13 nor the solenoid E can be operated until the proper circuit is closed at both breaks, so that, as is well understood, in order to operate a particular signal the two breaks in the local circuit controlling said signal must be simultaneously closed.

At the home station are a sending instrument G, the before-mentioned battery 35, a battery 36, a battery 37, a magnet 38, its armature 39, which is a terminal adapted to oscillate between contact with either the fixed terminal 40 or the fixed terminal 41, a pole-changer H, a magnet 42, its armature 43, which is connected to the movable terminals 44 and 45 of said pole-changer H, and a second manually-operable pole-changer I. The sending instrument comprises a fixed circular plate 46, which is provided with openings 47, the number of said openings corresponding to the number of teeth upon the before-mentioned ratchet-wheels 21. Said sending instrument also includes a rotatable shaft 48, upon which is mounted a toothed conducting-disk 49, the number of teeth in said disk corresponding to the number of teeth upon said ratchet-wheels 21, and also mounted upon said shaft and rotatable therewith is a contact-arm 50. Said shaft 48 is under the influence of a spring, and the disk 49 is normally held against movement by a suitable detent, such construction being well understood and being disclosed in my before-mentioned application, Serial No. 119,639. A plug 51 is adapted to be inserted in any of the openings 47 and to thus lie in the path of movement of said before-mentioned contact-arm 50. Normally the shaft 48 is held by its before-mentioned detent to cause the disk 49 and contact-arm 50 to assume the zero position. (Indicated by full lines in Fig. 1.) When, however, the detent is removed, the spring causes said shaft 48 to rotate in a well-understood manner until said contact-arm 50 engages the pin 51, whereupon the said shaft and its disk and contact-arm are arrested. A brush 52, suitably supported upon the sending instrument, coöperates with the teeth of the disk 49. Said brush 52 is in connection with one pole of the before-mentioned battery 36, as by the wire 53, and the other pole of said battery is connected, as by the wire 54, with one pole of said magnet 42, the other pole of said magnet being connected, as by the wire 55, with the said toothed disk 49, which is made of conducting material. When the disk 49 is at zero position, the brush 52 lies in a space between suitable teeth upon said disk. As the disk revolves, however, its teeth successively contact with said brush. Each time that a tooth makes such contact the

circuit is completed through the magnet 42, and the movable terminals 44 and 45 of the pole-changer H are therefore thrown into position to contact, respectively, with the central 5 terminal 56 and one side terminal 57 of said pole-changer, thus causing a current of one polarity to pass to the polarized magnet F. When the tooth which has been in contact with said brush 52 passes the same and the 10 brush drops into the space between such tooth and the next following tooth, the magnet 42 is deenergized, whereupon the armature 43, under the influence of the spring 43^a, returns to normal position and the said terminals 44 and 15 45 of said pole-changer H contact, respectively, with the side terminal 58 and the central terminal 56 of said pole-changer, whereupon a current of opposite polarity is sent through the said polarized magnet F. Thus 20 as the toothed disk 49 rotates the magnet F is alternately oppositely energized, and the magnet 29 is therefore alternately energized and deenergized. The central terminal 56 of said pole-changer H is connected, as by the 25 wire 59, with the before-mentioned armature-terminal 39, and the spring 60, controlling said armature-terminal, normally holds the latter in contact with the before-mentioned fixed terminal 40. This latter-mentioned terminal 30 40 is in connection with the said magnet F, so that as the said disk 49 rotates the said magnet is energized, as previously described. Preferably the terminal 40 is connected, as by the wire 61, with a brush 62 upon the sending instrument, and a second brush 63 upon said instrument is connected, as by the wire 64, with said magnet F. These brushes 62 and 63 are adapted to bear upon a circular conducting-strip 65 upon the said toothed 35 disk 49, there being a break between the ends of said conducting-strip and this break being preferably filled by a block of insulation 66, upon which the said brushes 62 and 63 rest when the said toothed disk is in zero position. 40 Thus when the said toothed disk is in such zero position the circuit through the said magnet F is broken. The terminals 44 and 45 of said pole-changer H are in connection with opposite poles of the before-mentioned battery 45 50, and the terminals 57 and 58 of said pole-changer H are grounded, as through the wires 67 and 68, the said magnet F being also connected with the ground, as through the wire 69. The terminal 41 is connected, as by the wires 55 70, 71, and 72, with one pole of the before-mentioned magnet 34, the other pole of said magnet being connected with the ground, as by the wires 73, 74, and 75. The before-mentioned plug or pin 51 is in connection with one 60 pole of the battery 37, as through the wire 76, and the opposite pole of said battery is connected, as by means of the wire 77, with one pole of the before-mentioned magnet 38, the opposite pole of said magnet being connected 65 to said contacting arm 50, as through the wire 78, whereby when the shaft 48 has rotated sufficiently and the contacting arm 50 comes to rest against said pin 51 said magnet 38 is energized and said armature-terminal 39 is thrown into contact with said fixed terminal 70 41, thus causing the current from the before-mentioned battery 35 to be sent through the before-mentioned magnet 34, whereupon the terminal 16 is caused to contact with the terminal 15. Thus rotation of said shaft 48 causes 75 movement of both the toothed disk 49 and the contact-arm 50. Rotation of said toothed disk causes the terminal 18 to be brought into contact with the terminal 17, and when this occurs the contact-arm 50 rests against the 80 plug 51, whereupon the terminal 16 is brought into contact with the terminal 15. Therefore rotation of said shaft 48 serves to complete the local circuit through the magnet 13 and its battery 14, whereupon the latch 7 is thrown 85 and the signal-paddle C is permitted to fall. To reset a signal-arm, it is only necessary to move the pin 51 into the next hole 47 of the sending instrument. This permits the toothed disk 49 and the contact-arm 50 of said sending 90 instrument to advance one step, and such advance serves to carry the terminal 18 into contact with the brush 27 and also to again bring the terminal 16 into contact with the terminal 15. This completes the circuit through the 95 local battery 14 and the solenoid E, whereupon the circuit through the solenoid D is completed and the signal-paddle C is restored to normal position in the manner previously explained. 100

Between the wires 70 and 71 is a sounder K, of any well-known or desired construction, adapted to operate upon the making and breaking of the circuit including the same, and make-and-break wheels 79 and 80 are connected, respectively, between the wires 74 and 75 and the wires 73 and 74. These make-and-break wheels are of the usual type found in such well-known devices as messenger-calls, the wire 75 terminating in a brush, which co-operates with the periphery of said wheel 79, and the wire 74 terminating in a brush which co-operates with the periphery of said wheel 80. Each make-and-break wheel is controlled by a spring, (81 and 82,) the respective springs being connected to crank-arms 110 83 and 84, as is common and well understood in connection with ordinary messenger-calls. Connected to the shaft 2 are oppositely-extending arms 85 and 86, and lever-arms 87 and 88 are loosely mounted upon the respective shafts which carry the said make-and-break wheels 79 and 80, these lever-arms being connected to the respective arms 85 and 86 by links 89 and 90. Thus as the shaft 2 is rocked in one direction by the falling of the 120 signal-paddle the lever-arm 87 is depressed in order to operate upon the crank-arm 84, and thus wind the spring which controls the make-and-break wheel 80, just as if said crank-arm were moved by hand, as is common in 125 130

messenger calls, while the lever-arm 88 moves away from the crank-arm 83 and permits the spring 81 (which has been previously wound) to cause the wheel 79 to rotate and to transmit a signal through the sounder K, the signal of course indicating that the signal-paddle C has dropped. When the signal-paddle is restored to normal position, the reverse rocking of said shaft 82 causes the lever-arm 88 to act upon the crank-arm 83, and thus rewind the spring controlling the make-and-break disk 79 and also causes the lever-arm 87 to release the crank-arm 84, whereupon the spring 82 causes the disk 80 to rotate, and a signal is thus sent through the sounder K, the signal in this instance indicating that the signal-paddle has been restored.

What may be termed the "main-switch mechanism" L (which includes the heretofore-mentioned disk 19) embodies a polarized magnet 91 and a coöperating armature 92, said parts being more clearly shown in Figs. 2 and 3, in which one pole of said magnet 91 is marked 93 and the other pole is marked 94. When the armature-lever 92 (which forms a stop-lever) is attracted by the pole 93, said lever permits the disk 19 to rotate freely. When, however, said armature-lever is attracted by the pole 94, the end of said lever lies in the path of movement of a suitable stop-pin or other projection 95 upon the disk 19, so that the movement of said disk is limited. The armature-lever and stop-pin of each main switch are so set that when said pin and lever are in contact and the movement of the disk is thus arrested said disk is in its zero position. The said magnet 91 has one of its poles connected with the before-mentioned wire 71 and its other pole connected with the before-mentioned wire 72, so that said magnet forms a part of the circuit including the before-mentioned magnet 34. Under the ordinary circumstances the armature-lever 92 lies in position out of the path of movement of said stop-pin 95 and any impulse sent through the magnet 91 is of such polarity that the pole 93 is energized. Should any of the main switches L get out of step and it be desired to bring all of the switches into proper relationship with each other, it is only necessary to send an impulse of opposite polarity through the magnet 91 of each switch and to then permit the toothed disk 49 of the sending instrument to make a complete revolution. By sending an impulse of opposite polarity through the magnet 91 of each main-switch mechanism the stop-lever 92 of each of said main-switch mechanisms is attracted by the pole 94 and thrown into the path of movement of the stop-pin 95. The toothed disk 49 of the sending instrument G being then permitted to make a complete revolution, the disk 19 of each main-switch mechanism is moved step by step in a manner which will be readily apparent, and

each disk is arrested in its zero position by means of its stop-pin 95 coming into engagement with the armature-lever 92. After the disks 19 of each switch mechanism L has thus been reset, a current of what may be termed "normal polarity" is sent through the magnet 91 of each said switch mechanism, whereupon the armature 92 of each such switch mechanism is withdrawn from the path of movement of the stop-pin 95. In order to control the polarity of the current through said magnets 91, the following-described mechanism is provided: A pivoted arm 96 carries terminals 97 and 98, which are connected, as by means of the wires 99 and 100, with opposite poles of the before-mentioned battery 35. At one end of the throw of said pivoted arm 96 are terminals 101 and 102, and at the opposite end of said throw are terminals 103 and 104, the terminals 101 and 103 being connected, as by means of a wire 105, and the terminals 102 and 104 being connected, as by means of a wire 106. If the pivoted arm 96 be at either end of its throw, the terminals 97 and 98 are in such connection with the terminals 101 and 102 or 103 and 104 that a current of such polarity as to energize the pole 93 of the magnet 91 can be transmitted to such magnet from the battery 35 when the remainder of the circuit including such magnet is closed. Intermediate the said fixed terminals at the ends of the throw of said pivoted lever 96 are contact-strips 107, 108, 109, and 110, with which the before-mentioned terminals 97 and 98 contact as the pivoted arm 96 is thrown from one position to its opposite position, the said strips 107 and 108 being in the arc described by the said terminal 97 and the said strips 109 and 110 being in the arc described by the said terminal 98. The strip 110 is grounded, as through the wire 111, and the strip 109 is connected, as through the wire 112, with the before-mentioned wire 71, which leads to one pole of the magnet 91. The strip 108 is connected to the strip 110, as by the wire 113, and the strip 107 is connected to the strip 109, as by the wire 114. It will therefore be apparent that as the pivoted arm 96 is swung to bring its carried terminals 97 and 98 upon the before-mentioned contact-strips the polarity of the current supplied to the magnet 91 is reversed, so that in order to reset the disks 19 of the various main switches L it is only necessary to throw the lever 96 into position to bring its carried terminals 97 and 98 into contact with the before-mentioned intermediate strips and to then permit the toothed disk 49 to rotate. After the toothed disk 49 has completed its rotation the lever-arm 96 is thrown into one of its extreme positions and the initial direction of the current from the battery 35 is restored. The wire 115 of the before-mentioned circuit 9 leads from the line and is connected to one of the before-mentioned terminals 23, the other of said termi-

nals 23 being connected by the wire 116 with one pole of the helix 8, while the other pole of said helix is grounded, as through the wire 117. One pole of the battery 14 is connected 5 by the wire 118 with one pole of the magnet 13, and the other pole of said magnet 13 is connected by the wire 119 with the brush 17. The other pole of said battery 14 is connected by the wire 120 with the armature-terminal 16, 10 and the coöperating terminal 15 is connected by the wire 121 with the shaft 20, which is in connection with the terminal 18. The brush 27 is connected by the wire 122 with one pole of the helix 26, the other pole of said helix 15 being connected by the wire 123 with the before-mentioned wire 118. One pole of the battery 28 is connected by the wire 124 with the terminal 31, and the other pole of said battery 28 is connected by the wire 125 with one 20 pole of the magnet 29, the other pole of said magnet being connected by the wire 126 with the armature-terminal 32.

The wire 69 does not lead directly to ground from the magnet F of the first station, but is 25 connected to the wire 64 at the next signal-station, so that the magnets F of the various stations are in a single circuit, the wire 69 from the last magnet in the series being grounded; also, the wire 75 does not lead directly to ground from the make-and-break 30 wheel 79 of the first station, but is connected to the wire 71 of the second station, so that all of the magnets 91 and 34, together with the make-and-break wheels 79 and 80 of the various 35 stations, are included in a single circuit, the wire 75 being grounded at the last station.

The construction of the main switch L is illustrated in Figs. 2 to 7. Referring now more particularly to said figures, 127 represents the base of the switch, from which rises 40 a supporting-arch 128, the before-mentioned lever 30 being pivotally supported upon said arch and being controlled by the before-mentioned magnets 29, suitably supported upon 45 the base, the structure thus far described being substantially similar to the well-known telegraph-sounder. In standards 131 is journaled the before-mentioned shaft 20, upon which is sleeved the before-mentioned disk 19, 50 this disk being adjustable circumferentially about the shaft and being fixed thereto in the present instance by means of the set-screw 132. The disk can therefore be placed in any desired relationship to the shaft circumferentially, so that it can be set to coöperate with 55 the mechanism for controlling any desired signal in the system. Fastened upon said shaft 20 to rotate therewith are the before-mentioned ratchet-wheel 21 and a second ratchet-wheel 133, the teeth of said wheels inclining in opposite directions and said wheels being conveniently fastened together, as shown in Fig. 4. Loosely mounted upon said shaft 20 is a bell-crank lever whose arm 134 has pivoted there-

to the before-mentioned pawl 22, which coöperates with the ratchet-disk 21, while the arm 135 of said bell-crank lever is connected by a link 136 to said lever 30, so that reciprocation of said lever serves through said pawl to advance the ratchet-disk 21 in a manner which will be readily apparent. A suitable locking-pawl 137 also coöperates with said ratchet-disk to prevent backward movement of the same. Journaled between suitable supports 75 138 is a rock-shaft 139, which carries a rock-arm 140 in the form of a stop-pawl, coöperating with the ratchet-disk 133. A second rock-arm 141 upon said rock-shaft is connected by a link 142 with said lever 30, so that at each downward movement of said lever 30 not only is the pawl 22 moved to advance the ratchet-disk 21 and its connected parts, including the disk 19, but the stop-pawl 140 is thrown in the path of movement of the appropriate tooth upon the disk 133 in order to prevent excessive forward movement of the shaft 20. The shaft 20 is in electrical connection with the wire 121, as previously explained, and the conducting-strip 18, carried by said disk 19, engages said shaft 20 and extends to 90 the periphery of said disk 19.

The before-mentioned brushes 17 and 27 are suitably supported upon the standard of the switch, as shown, and bear upon the periphery of said disk 19.

The polarized magnet 91, to which reference has been previously made, is supported upon the base 127 and coöperates with the stop-lever 92, as previously explained.

After the sounder has operated and the dispatcher is satisfied that the desired signal has been thrown the pin 51 is removed from the hole in the dial, whereupon the contact-arm 50 and its contact-disk 49 are moved through the remainder of the revolution which has been partly made, the parts coming to rest at the proper time. During the revolution of the said shaft the teeth of the contact-disk have engaged the contact-finger 52, and at each engagement of said parts every switch-dial 45 has been moved one step, so that when the contact-disk and the other parts of the sending instrument reach normal zero position each switch-dial stands in its normal position, ready for a second operation.

I am aware that minor changes in the construction, arrangement, and combination of the several parts of my device can be made and substituted for those herein shown and described without in the least departing from the nature and principle of my invention.

Having thus described the invention, what is claimed as new, and desired to be secured by Letters Patent, is—

1. In a system of the character indicated, a plurality of signals, a single sending instrument, connections between the said sending instrument and the several signals whereby

- any one of the signals can be separately operated by said instrument, and a connection between the instrument and the several signals whereby any single one of the signals 5 can, through the instrumentality of said instrument be restored to normal position, said instrument being operable for operating all of said signals and for restoring all of them; substantially as described.
- 10 2. In a system of the character indicated, the combination with a signal, of an operative mechanism adapted in its operation to render said signal operative, a second operative mechanism adapted in its operation to restore said 15 signal to normal position, a circuit controlling said first-mentioned operative mechanism, a circuit controlling said second-mentioned operative mechanism, a movable terminal included in each of said circuits, a terminal in 20 each of said circuits with which said movable terminal is adapted to be brought into contact at different times, means for moving said movable terminal, a switch in each of said circuits, and means for operating said switch; 25 substantially as described.
3. In a system of the character indicated, a signal, an operative mechanism adapted in its operation to render said signal operative, a second operative mechanism adapted in its operation to restore said signal to normal position, a circuit controlling said first-mentioned operative mechanism, a second circuit controlling said second - mentioned operative mechanism, a movable terminal included in 30 both said circuits, a terminal in each of said circuits with which said movable terminal is adapted to be brought into contact at different times, a switch in both said circuits, and a sending instrument including means whereby 35 40 when said movable terminal is brought into contact with either of said fixed terminals said switch in said circuits is operated to render effective the particular circuit with whose terminal said movable terminal is in contact; substantially as described.
4. In a system of the character indicated, the combination with a signal, of an operative mechanism through whose operation said signal is rendered operative, a second operative 45 mechanism through whose operation said signal is restored to normal position, a circuit controlling said first - mentioned operative mechanism, a second circuit controlling said second - mentioned operative mechanism, a movable terminal in both said circuits, a terminal in each of said circuits and adapted to be contacted by said movable terminal at different times, an operative mechanism for giving said movable terminal a step-by-step 55 movement, a circuit controlling said last-mentioned operative mechanism, a switch in both said first two mentioned circuits, an operative mechanism controlling said switch, and a send-

ing instrument including means for controlling the said circuits controlling said last two 65 mentioned operative mechanisms; substantially as described.

5. In a system of the character indicated, a signal, a source of energy, an operative mechanism through whose operation said signal is rendered operative, a second operative mechanism through whose operation said signal is restored to normal position, a circuit from said source of energy and including said first-mentioned operative mechanism, a second circuit from said source of energy and including said second-mentioned operative mechanism, a movable terminal included in both said circuits, a relatively fixed terminal in each of said circuits with which said latter-mentioned terminals said movable terminal is adapted to be brought into contact at different times, a switch in both of said circuits, and means for controlling said movable terminal and said switch; substantially as described. 85

6. In a system of the character indicated, a signal, an operative mechanism controlling the same, a circuit including said operative mechanism, two switches in said circuit, a circuit controlling one of said switches, another circuit controlling the other thereof, terminals in each of said last-mentioned two circuits, and a movable terminal common to both said last-mentioned two circuits and adapted to contact with either of said last-mentioned two 90 terminals for completing the particular circuit including the terminal with which said movable terminal is in contact; substantially as described.

7. In a system of the character indicated, a signal, an operative mechanism controlling the same, a circuit controlling said operative mechanism, two switches in said circuit, a source of energy, a terminal connected thereto, two terminals each of which is adapted to separately coöperate with said first-mentioned terminal, electrical connection between one of said two terminals and the operative mechanism for one of said switches, electrical connection between the other of said two terminals and the operative mechanism for the other of said switches, and means for causing electrical connection to be made between either of said two terminals and said terminal in connection with said source of energy; substantially as described. 100 105 110 115

8. In a system of the character indicated, a signal, an operative mechanism controlling the same, a circuit including said operative mechanism, two switches in said circuit, an operative mechanism for controlling each of said switches, a circuit including one of said switch-controlling operative mechanisms, another circuit controlling the other of said switch-controlling operative mechanisms, a terminal in 120 125 each of said last two mentioned circuits, a ter-

- 5 minal common to both of said last two mentioned circuits and adapted to electrically contact with either of said first two mentioned terminals, means whereby said terminal common to both said last two mentioned circuits is normally in contact with one of its said co-operating terminals, and a sending instrument including means for transmitting energy over said circuit whose terminal is normally in contact with said co-operating terminal and means whereby, at a desired time, said terminal common to both said switch-controlling circuits is brought into electrical contact with the other of its said co-operating terminals for causing energy to be transmitted over the circuit including said last-mentioned terminal; substantially as described.
- 10 9. In a system of the character indicated, a signal, an operative mechanism controlling the same, a circuit including said operative mechanism, two switches in said circuit, a controlling mechanism for each of said switches, a circuit including one of said switch-controlling mechanisms, another circuit including the other of said switch-controlling mechanisms, a relatively fixed terminal in each of said last two mentioned circuits, a movable terminal common to both said last two mentioned circuits and movable between said first two mentioned terminals, an operative mechanism controlling said movable terminal, a circuit including said operative mechanism, means whereby said movable terminal is normally in contact with one of its said co-operating terminals, a sending instrument including means for causing electrical impulses to be transmitted over the circuit including said last-mentioned relatively fixed terminal, said sending instrument also including terminals of said circuit which controls said before-mentioned movable terminal, one of said terminals included in said sending instrument being movable with respect to the other thereof during the operation of said sending instrument; substantially as described.
- 15 10. In a system of the character indicated, a signal, a circuit controlling the operation of said signal, two brushes in said circuit, a sending instrument, a conducting-strip in said sending instrument upon which said brushes are adapted to bear during the operation of said sending instrument, and a non-conducting portion between the end of said sending strip and adapted to receive said brushes when said sending instrument is inoperative; substantially as described.
- 20 11. In a system of the class described, a signal, means for rendering said signal operative, an operative mechanism for restoring said signal to normal position, a main-line circuit, a circuit from said main-line circuit including said operative mechanism, and means for controlling said last-mentioned circuit comprising a switch in the last-mentioned circuit, and a pole-changer; substantially as described.
- 25 12. In a system of the character indicated, a signal, means for rendering said signal operative, an operative mechanism for restoring said signal to normal position, a main-line circuit, a circuit from said main-line circuit including said operative mechanism, a switch in said last-mentioned circuit, a sending instrument, means whereby said sending instrument controls said means for rendering said signal operative, and means whereby said sending instrument also controls said switch; substantially as described.
- 30 13. In a system of the character indicated, a signal, an operative mechanism for rendering said signal operative, a second operative mechanism for restoring said signal to normal position, a circuit including said first-mentioned operative mechanism, a terminal in said circuit, a second circuit including said second-mentioned operative mechanism, a switch in said second circuit, a switch-operating mechanism, a third circuit including said switch-operating mechanism, a terminal in said third circuit, a movable terminal common to both said first circuit and said third circuit and adapted to coact with either of said first two mentioned terminals, and means for operating said movable terminal; substantially as described.
- 35 14. In a system of the character indicated, a signal, an operative mechanism for rendering said signal operative, a second operative mechanism for restoring said signal to normal position, a circuit including said first-mentioned operative mechanism, a terminal in said circuit, a second circuit including said second-mentioned operative mechanism, a switch in said second circuit, a switch-operating mechanism for operating said switch, a third circuit including said switch-operating mechanism, a terminal in said third circuit, a movable terminal common to both said first circuit and said third circuit and adapted to co-operate with said first two mentioned terminals, a switch common to both said first circuit and said third circuit, and means for causing said movable terminal to contact with both said first two mentioned terminals at different times and for causing said last-mentioned switch to be operated simultaneously with the contact of said movable terminal with either of said first two mentioned terminals; substantially as described.
- 40 15. In a system of the character indicated, a signal, means for rendering said signal operative, means for restoring said signal to normal position, means for automatically causing a signal to be transmitted when said first-mentioned signal is rendered operative, and means for causing a signal to be transmitted

when said first-mentioned signal is restored; substantially as described.

16. In a system of the character indicated, a signal, means for causing said signal to be rendered operative, means for causing said signal to be restored, two signal-sending mechanisms, a mechanism under the control of said first-mentioned signal for operating said signal-sending mechanisms, and means whereby 5 when said first-mentioned signal is rendered operative one of said signal-sending mechanisms is permitted to operate and the other of said signal-sending mechanisms is placed in operative condition, and means whereby when 10 said first-mentioned signal is restored said other of said signal-sending mechanisms is permitted to operate and said first separately-mentioned signal-sending mechanism is rendered operative, substantially as described.
17. In a system of the character indicated, a signal, a circuit controlling said signal and including a switch, step-by-step mechanism for operating said switch, a circuit including said switch-operating mechanism, a second switch 25 included in said last-mentioned circuit, and means whereby, for each step of movement of said first-mentioned switch, said last-mentioned switch is electrically thrown into circuit-forming position and electrically thrown 30 into circuit-breaking position; substantially as described.

18. In a system of the character indicated, a signal, a circuit controlling the same and including a step-by-step switch, switch-operating mechanism, a circuit controlling said switch-operating mechanism and including a second switch, a polarized magnet controlling the movable member of said second switch, a sending instrument, and means controlled by 35 said sending instrument for alternately energizing the opposite poles of said polarized magnet; substantially as described.

19. In a system of the character indicated, a signal, a circuit controlling the operation of 45 said signal and including a step-by-step switch, switch-operating mechanism, a circuit controlling said switch-operating mechanism and including a second switch, a polarized magnet controlling the movable member of said second switch, a circuit including said polarized magnet, a pole-changer in said circuit, a sending instrument, and means whereby said sending instrument in its operation causes operation of said pole-changer; substantially as described.

20. In a system of the character indicated, a plurality of signals, a step-by-step switch for each of said signals, a sending instrument controlling all of said switches, and means 50 whereby all of said switches can be corrected with respect to each other; substantially as described.

21. In a system of the character indicated, a plurality of signals, a step-by-step switch con-

trolling each of said signals, a stop member 65 upon each of said switches, a coöperating stop member for each of said switches, a central station, means for operating each of said switches from said central station, means for normally holding each of said coöperating 70 stop members in inoperative position, and means whereby each of said coöperating stop members can be thrown into stopping position from said central station; substantially as described.

22. In a system of the character indicated, a plurality of signals, a step-by-step switch controlling each of said signals, a stop member upon each of said switches, a coöperating stop member for each of said switches, a polarized 80 magnet controlling each of said coöperating stop members, a circuit including said polarized magnets, a pole-changer in said circuit, and means for operating said several switches; substantially as described.

23. In a system of the character indicated, the combination with a switch including a rotatable disk, a conductor carried by said disk, a terminal coöperating with said conductor, and means for actuating said disk by a step-by-step movement, of a stop member connected to said disk, a coöperating stop member, and means for throwing said coöperating stop member into and out of the path of movement of said first-mentioned stop member; 95 substantially as described.

24. In a switch of the character indicated, a rotatable disk, a conductor carried by said disk, a terminal coöperating with said conductor, and means for moving said disk by a step-by-step movement, of a stop member connected to said disk, a polarized magnet, and a stop-lever pivotally supported between the poles of said magnet; substantially as described.

25. In a switch of the character indicated, a 105 rotatable shaft, a disk fastened thereto, a conductor carried by said disk, a terminal coöperating with said conductor, a ratchet-disk fastened to said shaft, an arm loosely mounted upon said shaft, a pawl carried by said arm and coöperating with said disk, a lever, and operative connection between said lever and said pawl-carrying arm; substantially as described.

26. In a switch of the character indicated, a 115 rotatable shaft, a disk fastened upon said shaft, a contact member carried by said disk, a terminal coöperating with said contact member, a ratchet-disk fastened upon said shaft, a bell-crank lever loosely mounted upon said shaft, a pawl upon one arm of said bell-crank lever and coöperating with said ratchet-disk, a lever and a link connecting said lever and the other arm of said bell-crank lever; substantially as described.

27. In a switch of the character indicated, a 125 rotatable shaft, a disk fastened upon said shaft, a conductor carried by said disk, a terminal

coöoperating with said conductor, a ratchet-disk fastened upon said shaft, an operating-lever, a rock-shaft, a pawl upon said rock-shaft and coöoperating with said ratchet-disk to limit the movement of the same, a rock-arm upon said rock-shaft and a link between said lever and said rock-arm; substantially as described.

In testimony whereof I hereunto affix my signature, in the presence of two witnesses, ¹⁰ this 25th day of April, 1904.

JAMES E. ALLISON.
